US00D968451S

(12) **United States Design Patent** (10) **Patent No.:** **US D968,451 S**
(45) **Date of Patent:** **** Nov. 1, 2022**

(54) **DISPLAY SCREEN OR PORTION THEREOF
WITH GRAPHICAL USER INTERFACE**

(71) Applicant: **RITE-HITE HOLDING
CORPORATION**, Milwaukee, WI
(US)

(72) Inventors: **James C. Boerger**, Franksville, WI
(US); **Richard Mews**, Bonduel, WI
(US); **Kenneth C. Bowman**,
Cedarburg, WI (US)

(73) Assignee: **RITE-HITE HOLDING
CORPORATION**, Milwaukee, WI
(US)

(**) Term: **15 Years**

(21) Appl. No.: **35/001,714**

(22) Filed: **Jul. 22, 2019**

(80) **Hague Agreement Data**

Int. Filing Date: **Jul. 22, 2019**

Int. Reg. No.: **DM/210266**

Int. Reg. Date: **Jul. 22, 2019**

Int. Reg. Pub. Date: **Sep. 25, 2020**

Related U.S. Application Data

(63) Continuation of application No. PCT/US2019/021514, filed on Mar. 9, 2019.

(51) **LOC (13) Cl.** **14-04**

(52) **U.S. Cl.** **USPC** **D14/487**

(57) **CLAIM**

The ornamental design for a display screen or portion thereof with graphical user interface, as shown and described.

DESCRIPTION

1.-3. Display screen or portion thereof with graphical user interface

1.0 : Front view of a first image of a display screen or portion thereof with graphical user interface;

2.0 : Front view of a second image thereof; and

3.0 : Front view of a third image thereof.

Figures 1-3 show a display screen or portion thereof with graphical user interface; the outer broken lines indicate a display screen or portion thereof and form no part of the claimed design; the features shown in the inner broken lines

(Continued)

and lighter gray text and dotted lines illustrate portions of the graphical user interface that form no part of the claimed design.

1 Claim, 3 Drawing Sheets
